(57) **CLAIM**

The ornamental design for a tray assembly for a vial and vial adapter, as shown and described.

DESCRIPTION

FIG. 1 is a top, left, front perspective view of a tray assembly for a vial and vial adapter showing our new design; FIG. 2 is a bottom, right, front perspective view thereof; FIG. 3 is a top plan view thereof, wherein an inner tray is not shown;

FIG. 4 is a bottom plan view thereof;

FIG. 5 is a left side elevation view thereof, the right side view being a mirror image of this view is not shown;

FIG. 6 is a rear elevation view thereof;

FIG. 7 is a front elevation view thereof;

FIG. 8 is a top, left, front perspective exploded view thereof, wherein the inner tray is shown separate from the outer tray; FIG. 9 is a top plan view thereof, rotated 90 degrees and showing a vial and vial adapter in a disengaged state; and, FIG. 10 is a top plan view thereof, rotated 90 degrees and showing a vial and a vial adapter in an engaged state.

The broken line showing is for the purpose of illustrating environmental structure and forms no part of the claimed design.
